ABSTRACT OF THE DISCLOSURE

Method and apparatus for washing materials suspended in a liquid while maintaining the liquid, materials and interior of the apparatus in a sterile condition. Sterile air entrapped in a centrifuge is displaced into a first sterile, collapsed flexible pouch for storage and then subsequently used to force processed blood cells in liquid suspension from the centrifuge into a second sterile, collapsed flexible pouch. The need for purifying nitrogen and controlling its pressure to effect the necessary liquid displacements in the apparatus is eliminated and the transfer of liquid within the system may be accomplished while the system is being moved from one area to another.

This invention relates to apparatus and method for processing materials suspended in a liquid under sterile conditions and more particularly to washing blood cells in a centrifuge in a fail-safe sterile environment.

Long-term storage of human blood requires that it be frozen in a liquid medium to protect it during storage. Subsequent to its collection from a donor the blood is pumped into a centrifuge rotor wherein the intracellular and intercellular water is replaced by glycerol, and then the resulting glycerolized cells are transferred from the rotor into a plastic pouch, frozen and stored. When the blood is to be used, it is brought up to temperature, pumped into a centrifuge rotor and the glycerol is replaced by a suitable saline liquid while the red cells remain in the centrifuge. Subsequently, the cells are removed from the rotor while suspended in the saline liquid.

The introduction of the blood into the rotor, the concentration of the red cells, the replacement of the natural intercellular and intracellular water with glycerol and the removal of the glycerolized blood prior to storage, as well as the introduction of the stored blood into the rotor, the replacement of the glycerol with saline liquid and the removal of the reconstituted blood from the rotor must be accomplished within a fail-safe, sterile environment. It has been customary in the prior art methods and apparatus to use purified nitrogen gas under pressure to force the blood or liquid containing the suspended cells from one container to another. The use of pressurized nitrogen for this purpose has several inherent disadvantages. First, it means that the nitrogen cylinders themselves add another piece of equipment which must be brought into, stored and taken from the preparation room, and consequently, all transfers of liquid in the system must be carried out in one area. Second, the requirement that the nitrogen be purified, such as by passing it through an "absolute" filter, introduces an additional step into the process and, hence, introduces another point at which human error may enter. Finally, it is possible to err in controlling the pressure under which the nitrogen is used, and if the pressure is too high, it is possible that some of the system components (pouches and tubing) may be ruptured.

It would, therefore, be desirable to have a fail-safe way of supplying and handling a sterile gas within a centrifuging system while at the same time minimizing the amount and size of equipment required and permitting the entire system to be portable.

2

It is, therefore, a primary object of this invention to provide a method of transferring liquid within a sterile system which eliminates the need for an external source of purified pressurized gas and, hence, eliminates one or 5 more of the possibilities for error in the processing of the liquid. It is another object of this invention to provide an improved method for transferring red blood cells suspended in liquid within a system which must be kept in a sterile condition. Yet another object is to provide a 10 method of the character described which permits the fluid transfer within the system to be carried out as the system is moved from one area to another.

It is an additional primary object of this invention to provide apparatus for processing a liquid in a sterile condition. It is a further object to provide apparatus of the character described which eliminates the use of an externally supplied, pressurized and purified gas and which minimizes the apparatus components required. Still another object is to provide such apparatus which is 20 completely and easily portable. Other objects of the invention will, in part, be obvious and will, in part, be apparent hereinafter.

The invention accordingly comprises the several steps and the relation of one or more of such steps with respect 25 to each of the others, and the apparatus embodying features of construction, combination of elements and arrangement of parts which are adapted to effect such steps, all as exemplified in the following detailed disclosure, and the scope of the invention will be indicated 30 in the claims.

For a fuller understanding of the nature and objects of the invention, reference should be had to the single drawing, which is a side elevational view of the apparatus of this invention.

35 Although the method and apparatus of this invention may be used for purposes other than processing blood, it will be convenient to describe the invention in terms of processing blood cells in a centrifuge. It should be noted that the handling of blood places the most stringent requirements known on any system and, hence, any method and apparatus suitable for use with blood is capable of meeting the requirements for sterile conditions in processing other liquids.

In the method of this invention, gas (normally air) is 45 entrapped in the centrifuge rotor of a blood machine during its assembly and is maintained within the centrifuge rotor during sterilization. This is normally done by enclosing the centrifuge rotor in a suitable plastic container resembling a "skin" package and passing ethylene oxide 50 through the container walls. Thus, the air entrapped in the rotor is sterilized and remains sterile throughout the use of the rotor. Alternatively, the air may be flushed out with an inert gas, such as nitrogen after assembly of the rotor but before it is enclosed in the "skin" package. 55 When liquid with blood cells suspended therein is introduced into the rotor the sterile air is displaced into a sterile, collapsed flexible plastic pouch. As the liquid on the cells is gradually changed in the washing procedure, the spent wash liquid is also transferred into the flexible pouch in a manner to maintain the air above the liquid. When washing is completed, pressure is applied to the flexible pouch to force the stored sterile air to return to the rotor and effect some displacement of the liquid and cells suspended therein to start a siphoning action which causes the liquid containing the suspended cells to be transferred to a second collapsed flexible plastic pouch. Flow control means are provided and it is also possible to use the system in such a way as to direct fluid back into a pumping system which may be associated with the centrifuge. Thus, the system remains completely closed, requires no externally supplied pressurized gas and is flexible in its use.

The drawing illustrates the apparatus of this invention in a side elevational view as it is embodied in blood centrifuging equipment. The centrifuge rotor 10, in which the red cells are to be glycerolized or deglycerolized, has a stationary inlet tube 11 and a stationary discharge tube 30, the seal between the rotating and stationary components of the rotor being preferably that described in U.S. Pat. 3,409,213. This centrifuge rotor is formed of rigid walls and is supported during centrifugation on a suitable spindle 9 and when it is not being rotated on any suitable support (not shown), such as the center tray assembly of the transport dolly described in my copending application Ser. No. 863,122 filed on Oct. 2, 1969, now U.S. Pat. 3,552,577 for Apparatus for Transporting Liquids.

Removably attached to inlet tube 11 is plastic tubing 12 which is internally sterile and which has an externally actuatable clamp 13 associated with it. The purpose of clamp 13 is to totally constrict the tubing 12 so as to prevent the flow of fluid therethrough. Tubing 12 is attached to or integral with manifold 14. Tubing 12 may have a series of partial constrictions 15 to improve the mixing of fluid flowing therethrough. The manifold 14 may in turn be in fluid communication with a source of liquid-suspended red cells through tubing 16 and with one or more processing liquid sources through tubings 17-20. Although the manner in which the liquid along with any material suspended therein is delivered to tubing 12 is not part of this invention manifold 14 and tubings 16-20 will preferably be the pump harness shown in FIG. 8 of U.S. application Ser. No. 768,692, filed in my name on Oct. 18, 1969, and the fluid pumping system will be that described in Ser. No. 768,692 now U.S. Pat. 3,565,286.

Communicating with tubing 12 through a fluid-tight, sterile connection is a flexible tubing 25 which also has a clamp 26 of the same type as clamp 13. Tubing 25 is, of course, internally sterile and it terminates at its open end in a connection with a sterile fluid container 27 having a suitable tubing connection welded to it. Container 27 is provided as a flat, collapsed plastic pouch.

If container 27 is to be used to store glycerolized blood cells, then it must be of a material which is amenable to the freezing and thawing temperatures to be used. It must also, of course, be a material inert to the liquid and suspended matter stored therein.

It is within the scope of this invention to use any other suitable alternative apparatus components which perform the same role as the apparatus embodiment illustrated in the drawing. Thus, for example, a Y joint may be used to effect the juncture of tubings 12 and 25. It is also, of course, possible to use a three-way cock or valve to effect this juncture, in which case the clamps may be eliminated.

The plastic pouch 27 has one or more loops 28 affixed to the top which serve as means to suspend the pouch on hooks 29 or on other suitable holding means. Inasmuch as the transfer of liquid and suspended material is to be effected by a siphoning action, it is necessary that pouch 27 be located below the centrifuge rotor 10. Thus, if the centrifuge rotor is supported on the center tray assembly shown in U.S. Pat. 3,552,577 the bag 27 may be hung on one or more hooks of the bag support assembly shown and described in this copending application.

A fluid conduit 31 (normally also a flexible plastic tubing) connects the rotor discharge tube 30 with a flat, collapsed flexible plastic pouch 32, the connection being through the connection welded to pouch 32. In a manner similar to that described for pouch 27, pouch 32 is hung by one or more loops 33 (or other suitable suspending means) to hangers 34. The location of pouch 32 will depend upon how the air and liquid which are to be contained therein are to be used. This will be discussed in a description of the operation of the apparatus. By expansion and contraction of the volume of pouch 32 sterile air, present originally in the centrifuge, may be transferred between the centrifuge and the pouch.

In operation, the skin package in which the centrifuge rotor was enclosed and sterilized is removed and the remaining components are attached. Typically, these components will also be packaged in some suitable form of "skin" packages for sterilizing in the same manner as the centrifuge rotor. Rather than packaging pouch 27 and the pump harness with the tubings in one package and pouch 32 with tubing 31 in another package, it is possible to encase the entire apparatus in a single package for sterilization and storing. All of the apparatus assembly steps are carried out in a clean air, laminar-flow zone.

After the rotor is placed on its spindle for rotation, clamp 26 is actuated to close off fluid flow through tubing 25 and clamp 13 is actuated to open a fluid flow path through tubing 12. As the liquid containing the suspended blood cells flows into centrifuge rotor 10 the sterilized air (or other gas) contained in the rotor is displaced and forced into pouch 32. Subsequently, as more liquid (for glycerolization or deglycerolization) is pumped into rotor 10, a quantity of the liquid present in the rotor is also pumped out into pouch 32 which is so oriented as to maintain the air above the liquid. Thus, the composition of the liquid in which the cells are suspended is changed.

When the desired liquid composition in the rotor is attained, clamp 13 is actuated to cut off liquid flow through tubing 12 into rotor 10 and the centrifuge rotation is stopped. Clamp 26 is then actuated to permit fluid flow through tubing 25 into flexible pouch 27 which has up to this time remained in a collapsed flat condition. Then by applying hand pressure to the walls of flexible pouch 32 the stored sterile gas is forced to return into rotor 10 to cause the liquid and suspended cells to flow upwardly through the inlet tube 11 (which as shown in the dotted line extends to the bottom of the rotor) and into tubing 25. Once tubing 25 is filled a siphoning action is initiated (by virtue of the relative positions of rotor 10 and pouch 27) and the liquid and suspended material is transferred from rotor 10 to pouch 27.

When this liquid transfer has been completed, tubing 25 is dielectrically sealed above the connection with pouch 27 and then cut at the seal to form a fluid-tight, sterile pouch of material. The remaining portion of the apparatus is then disassembled for appropriate disposition.

In some modes of operation, it may be desirable to return the liquid collected in pouch 32 back through the centrifuge to a pump or other apparatus attached to inlet 11. This may be readily accomplished by closing off the fluid flow in tubing 25, opening the fluid path of tubing 12 and inverting pouch 32 so that the liquid is on the bottom and gas on top. Then by means of gas pressure, hydraulic forces or a combination of both, the liquid may be driven at a controlled rate of flow back through rotor 10 and out through inlet 11.

Inasmuch as the entire system is closed, complete in itself and easily manageable it is portable, and liquid transfer within the system may be carried out while the system is transported from area to area, thus making maximum use of the centrifuge and the auxiliary equipment associated with it. Such transporting is conveniently carried out on the transport dolly described in the above-identified U.S. Pat. 3,552,577.

Thus, through the use of sterilized flat collapsed plastic pouches, the flow-controlled connecting tubes and the sterile air in the rotor, it is possible to effect transfer of liquids within the sterile system without the need for an externally supplied gas-pressurizing system and without the possible dangers associated with such an external pressurizing system. Moreover, the apparatus and method of this invention are flexible in application to various systems and flow patterns required.

It will thus be seen that the objects set forth, among those made apparent from the preceding description, are efficiently attained and, since certain changes may be made in carrying out the above method and in the construction set forth without departing from the scope of the invention.

tion, it is intended that all matter contained in the above description or shown in the accompanying drawing shall be interpreted as illustrative and not in a limiting sense.

I claim:

1. An apparatus for processing a liquid by treatment with another treating liquid while maintaining the interior of the apparatus in a sterile condition, comprising in combination:
  - (a) a source of said liquid and said treating liquid;
  - (b) an internally sterilizable fluid-tight vessel having 10 separate fluid inlet and fluid discharge means;
  - (c) a first fluid conduit providing fluid communication between said inlet means of said vessel and said source of said liquid and said treating liquid;
  - (d) a first flexible-wall pouch in fluid communication 15 with said first fluid conduit through a second fluid conduit;
  - (e) means to selectively control the flow of fluid in said first and second conduits; and
  - (f) a second flexible-wall pouch in fluid communication 20 with said discharge means of said vessel through a third fluid conduit.
2. An apparatus in accordance with claim 1 wherein said first, second and third fluid conduits are flexible tubing.
3. An apparatus in accordance with claim 1 wherein said first and second fluid conduits communicate through a Y connection and said means to selectively control the flow of fluid therethrough comprises externally actuatable clamp means associated with each of said first and second conduits.
4. An apparatus in accordance with claim 1 including means to hold said first pouch at a level below said vessel.
5. An apparatus for treating blood with a liquid, comprising in combination: 35
  - (a) a source of said blood and said liquid;
  - (b) a centrifuge rotor having separate fluid inlet and fluid discharge means;
  - (c) a first flexible tubing providing fluid communication 40 between said inlet means of said rotor and said source of said blood and said liquid;
  - (d) a first flexible-wall plastic pouch in fluid communication with said first flexible tubing through a second flexible tubing;
  - (e) means to selectively control the flow of fluid in 45 said first and second flexible tubings; and
  - (f) a second flexible-wall plastic pouch in fluid communication with said discharge means of said rotor through a third flexible tubing.
6. An apparatus in accordance with claim 5 wherein said first and second pouches are in a flat collapsed condition and the components of said apparatus are encased in semi-permeable sealing means adapted to permit sterilization of said components and any gas contained therein.
7. An apparatus in accordance with claim 5 wherein said first and second flexible tubings communicate through a Y connection and said means to selectively control the

flow of fluid therethrough comprise externally actuatable clamp means associated with each of said first and second flexible conduits.

5 8. A method of processing a liquid by treatment with liquid while maintaining the treating system in a sterile condition, comprising the steps of:

- (a) introducing a first liquid into a vessel containing sterile gas and simultaneously displacing said gas into a second collapsed flexible sterile pouch thereby to store said sterile gas;
- (b) supplying a second liquid to said vessel and simultaneously transferring spent liquid from said vessel into said second flexible pouch while maintaining said gas above said liquid in said pouch;
- (c) discontinuing the supply of said liquid into said vessel; and
- (d) forcing said sterile gas from said second flexible pouch back into said vessel thereby to displace said liquid and to discharge a portion of it under the pressure of said sterile gas and then discharge the remaining portion under siphoning action into a first collapsed flexible sterile pouch.

9. A method in accordance with claim 8 wherein said first liquid has blood cells suspended therein.

25 10. A method in accordance with claim 8 wherein said sterile gas is air.

11. A method of treating blood cells in a sterile environment, comprising the steps of:

- (a) introducing blood cells suspended in a liquid into a centrifuge rotor containing sterile gas and simultaneously displacing said gas into a second collapsed flexible sterile pouch thereby to store said sterile gas;
- (b) while centrifuging said cells supplying a treating liquid to said rotor and simultaneously transferring spent liquid from said rotor into said second pouch while maintaining said gas above said spent liquid in said second pouch;
- (c) discontinuing centrifugation and the supply of said liquid into said rotor;
- (d) forcing said sterile gas from said first flexible pouch back into said rotor thereby to displace liquid having cells suspended therein and to discharge a portion of it under the pressure of said sterile gas and then discharge the remaining portion under siphoning action into a first collapsed flexible sterile pouch.

45 12. A method in accordance with claim 11 wherein said gas is air entrapped in said rotor during its assembly.

[57] ABSTRACT

Method and apparatus for washing materials suspended in a liquid while maintaining the liquid, materials and interior of the apparatus in a sterile condition. Sterile air entrapped in a centrifuge is displaced into a first sterile, collapsed flexible pouch for storage and then subsequently used to force processed blood cells in liquid suspension from the centrifuge into a second sterile, collapsed flexible pouch. The need for purifying nitrogen and controlling its pressure to effect the necessary liquid displacements in the apparatus is eliminated and the transfer of liquid within the system may be accomplished while the system is being moved from one area to another.

REEXAMINATION CERTIFICATE
ISSUED UNDER 35 U.S.C. 307.THE PATENT IS HEREBY AMENDED AS
INDICATED BELOW.

Matter enclosed in heavy brackets **[ ]** appeared in the patent, but has been deleted and is no longer a part of the patent; matter printed in italics indicates additions made to the patent.

AS A RESULT OF REEXAMINATION, IT HAS
BEEN DETERMINED THAT:

The patentability of claims 8-10 is confirmed.

Claims 1, 5, and 11 are determined to be patentable as amended:

Claims 2-4, 6, 7, and 12, dependent of amended claims, are determined to be patentable.

New claims 13-18 are added and determined to be patentable.

1. An apparatus for processing a liquid by treatment with another treating liquid *within a fluid-tight vessel* while maintaining the interior of the apparatus in a sterile condition **[ ]** comprising in combination:

- (a) a source of said liquid and *a source of said treating liquid*;
- (b) an internally **[sterilizable]** sterilized fluid-tight vessel having *a sterile gas entrapped therein; said sterile gas comprising a gaseous means for enabling transfer of liquid and separate fluid inlet and fluid discharge means*;
- (c) a first fluid conduit providing fluid communication between said inlet means of said vessel and said source of said liquid and *said source of treating liquid*;
- (d) a first flexible-wall pouch in fluid communication with said first fluid conduit through a second fluid conduit;
- (e) means to selectively control the flow of fluid in said first and second conduits; and
- (f) a second flexible-wall pouch *constituting the only item in fluid communication with said discharge means of said vessel through a third fluid conduit said third fluid conduit constituting the only path of fluid communication to or from said second flexible-wall pouch*.

5. An apparatus for treating blood with a liquid, comprising in combination:

- (a) a source of said blood and *a source of said liquid*;
- (b) a centrifuge rotor containing *an entrapped sterile gas contained in said rotor during sterilization and having separate fluid inlet and fluid discharge means*;
- (c) a first flexible tubing providing fluid communication between said inlet means of said rotor and *said source of said blood and said source of liquid*;
- (d) a first flexible-wall plastic pouch in fluid communication with said first flexible tubing through a second flexible tubing;

5

2

(e) means to selectively control the flow of fluid in said first and second flexible tubings; **[and]**

(f) a second flexible-wall plastic pouch *constituting the only item in fluid communication with said discharge means of said rotor through a third flexible tubing*;

(g) *means for transferring a volume of said sterile gas from said rotor to a second flexible-wall plastic pouch through said third flexible tubing for storage; and*

(h) *means for returning a volume of the sterile gas stored in said second flexible-wall plastic pouch to said rotor*.

11. A method of treating blood cells in a sterile environment, comprising the steps of:

(a) introducing blood cells suspended in a liquid into a centrifuge rotor containing sterile gas and simultaneously displacing said gas into a second collapsed flexible sterile pouch thereby to store said sterile gas;

(b) while centrifuging said cells supplying a treating liquid to said rotor and simultaneously transferring spent liquid from said rotor into said second pouch while maintaining said gas above said spent liquid in said second pouch;

(c) discontinuing centrifugation and the supply of said liquid into said rotor;

(d) forcing said sterile gas from said **[first]** second flexible pouch back into said rotor thereby to displace liquid having cells suspended therein and to discharge a portion of it under the pressure of said sterile gas and then discharge the remaining portion under siphoning action into a first collapsed flexible sterile pouch.

13. *An apparatus in accordance with claims 1 or 5 in which the sterile gas is comprised of air.*

14. *Apparatus in accordance with claim 5 in which the combination of blood source, liquid source, centrifuge rotor with entrapped sterile gas, first and second pouches and first, second, and third tubing comprise a self-contained sterile system having no fluid communication with an external source of sterile gas.*

15. *An apparatus for treating blood with a liquid by washing blood cells in a centrifuge rotor with a liquid wash solution in a closed sterile environment requiring no externally supplied pressurized gas for displacing fluid comprising in combination:*

- (a) *a source of said blood and a source of said liquid wash solution*;
- (b) *a internally sterilized fluid-tight centrifuge rotor vessel having separate fluid inlet and fluid discharge means, said vessel containing a sterilized gas entrapped therein during sterilization of said rotor vessel*;
- (c) *a first flexible fluid tubing providing fluid communication between said inlet means of said rotor vessel and said source of said blood and said liquid by being connected at one end thereof to the fluid inlet means of said rotor vessel, the remaining end being connected to a pair of flexible fluid tubings, one of which is adapted to be connected in an aseptic manner to said source of said blood cells to be washed, the second of which is adapted to be connected to said source of said liquid wash solution*

(d) *a second flexible fluid tubing connected at one end thereof to the fluid inlet means of said vessel through said first flexible fluid tubing, the remaining end being coupled to a first flexible-wall plastic pouch adapted to contain washed blood cells thereby to place said first flexible-wall plastic pouch in fluid communication with said second flexible fluid tubing*

55

60

65

- cation with said first flexible fluid tubing through a second flexible fluid tubing;
- (e) a third flexible fluid tubing connected at one end thereof to the fluid discharge means of said rotor vessel, the remaining end being coupled to a second flexible wall pouch adapted to contain spent wash solution thereby to place said second flexible-wall plastic pouch in fluid communication with said fluid discharge means of said rotor vessel through said third flexible fluid tubing, said second flexible-wall plastic pouch constituting the only item in fluid communication with said fluid discharge means; and
- (f) means for transferring a substantial volume of said sterilized gas from said rotor vessel through said third flexible conduit to said second flexible-wall pouch and 15 for returning a substantial volume of said sterilized gas through said third flexible conduit to said rotor vessel as blood cells washed in said rotor vessel are transferred to said first flexible-wall pouch by selectively controlling the flow of fluid in said first and 20 second flexible fluid tubings.

16. The apparatus of claim 15 wherein the sterilized gas is air.

17. An apparatus for treating blood with a liquid by washing blood cells in a centrifuge rotor with a liquid wash 25 solution in a closed sterile system requiring no externally supplied pressurized gas comprising in combination:

- (a) a source of said blood cells and a source of said liquid wash solution;
- (b) a internally sterilized fluid-tight centrifuge rotor 30 vessel having separate fluid inlet and fluid discharge tube means, said vessel containing a sterilized gas entrapped therein during sterilization, said sterilized gas comprising a gaseous means for enabling transfer of liquid in said system;
- (c) a first flexible fluid tubing connected at one end thereof to the fluid inlet tube means of said rotor vessel, the remaining end being connected to a pair of 35 flexible fluid conduits, one of which is adapted to be

- connected to said source of blood cells to be washed, the second of which is adapted to be connected in an aseptic manner to said source of liquid washing solution, said first flexible fluid tubing thereby providing a path of fluid communication between said inlet means of said rotor vessel and said source of said liquid washing solution and said source of blood cells;
- (d) a first flexible-wall plastic pouch in fluid communication with said first flexible tubing, through a second flexible fluid tubing said second flexible fluid tubing connected at one end thereof to the fluid inlet tube means of said rotor vessel through said first flexible fluid conduit, the remaining end being coupled to said first flexible-wall plastic pouch, which is adapted to contain washed blood cells;
- (e) a third flexible fluid tubing connected at one end thereof to the fluid discharge tube of said vessel, the remaining end being coupled to a second flexible-wall plastic pouch adapted to contain spent wash solution, said third flexible fluid tubing thereby providing a path of fluid communication through said third flexible tubing between the fluid in said vessel, the discharge means of said vessel, the second flexible wall pouch, and the fluid in said second flexible-wall pouch, said second flexible wall pouch being the only item in fluid communication with said discharge means;
- (f) means to selectively control the flow of fluid in said first and second flexible tubings, whereby the sterile gas in said rotor vessel is transferred from said vessel by introduction of fluid into the fluid inlet tube means and sterile gas is stored in said second flexible-wall plastic pouch to enable transfer of liquid from said rotor vessel back through said inlet tube means to said first flexible wall plastic pouch.

18. The apparatus of claim 17 wherein the sterilized gas is air.
